UNITED STATES PATENT OFFICE.

FRANCIS X. GARTLAND, OF PHILADELPHIA, PENNSYLVANIA.

EYEGLASSES.

SPECIFICATION forming part of Letters Patent No. 770,001, dated September 13, 1904.

Application filed July 27, 1903. Serial No. 167,066. (No model.)

To all whom it may concern:

Be it known that I, FRANCIS X. GARTLAND, a citizen of the United States, residing at Philadelphia, in the county of Philadelphia and State 5 of Pennsylvania, have invented certain new and useful Improvements in Eyeglasses, of which the following is a specification.

This invention relates to eyeglasses, and more especially to the means for securing the 10 spring and guards in manner to obviate the use of screws, which are constantly liable to work loose and allow the parts to become detached, and is an improvement on the Patent No. 733,639, issued to me July 14, 1903, and 15 my application, Serial No. 138,174, filed January 7, 1903. As in the previous inventions, the spring and guards are united and secured in a receptacle at the top of the posts, but in a more simple, inexpensive, and practical manner, as will be fully set forth in the specification.

The invention is illustrated in the accompanying drawings, in which—

Figure 1 shows a pair of eyeglasses having 25 posts with inclosed receptacles for the spring and guards. Fig. 2 is an end view of the receptacle. Fig. 3 is a section on line $\alpha\alpha$, Fig. 2, with the interlocking projection on the spring and the locking-plate inserted below 30 the guard. Fig. 4 is a section on line $\alpha\alpha$, Fig. 2, with the interlocking projection on the guard and the locking-plate inserted above the guard.

Similar figures of reference indicate similar 35 parts throughout the views.

The lenses 1 are secured to posts 2 in any suitable manner, as illustrated, or to frames, as shown in the previous inventions. The posts 2, as in the previous inventions, have 40 receptacles 3 at their tops composed of top walls 4, bottom walls 5, and side walls 6 7, leaving open ends 8 9 for the insertion of the spring 10 and guard 11. In Fig. 3 the spring 10 is above the guard 11, and a projection 12 45 on the guard 11 passes through an aperture 13 in the spring 10 and enters an aperture 14 in the top wall 4, while locking-plate 15 is forced into the receptacle between guard 11 and wall 5, securing all the parts from 50 placement until the locking-plate is with-

drawn, an offset 16 in guard 11 assisting in its security. Opposite aperture 14 in wall 4 is an aperture 17 in wall 5.

As in some instances and for special forms of guards it is more advantageous and desirable to have the projection 12 formed on the spring than on the guard, the manner of their interlocking and securing with such construction is shown in Fig. 4, where projection 12 is on the spring 10, passes through 55 an aperture 13 in the guard 11 and into aperture 17 in the wall 5, while locking-plate 15 is forced into the receptacle between spring 10 and wall 4, and the offset 16 is on spring 10. Thus it will be seen that by having apertures 14 and 17 opposite, the post and its receptacle is adapted for use with either the spring having projections and the guards having apertures, or vice versa, and projection 12 may be placed in aperture 14 or 17 to suit 60 65 any combination of springs, guards, and interlocking projections.

I claim—

1. In eyeglasses, the combination of posts 75 having receptacles composed of top, bottom and side walls forming open ends, with members comprising a spring and guards, a projection on one member which passes through an aperture in the other member and into an aperture in a wall of the receptacle, and locking-plates inserted in the receptacles to retain the spring, the guards and the projections in position in the receptacle.

2. In eyeglasses, posts having closed receptacles except as to their ends, which are 85 open, a spring having projections passing through the guards, and into a wall of the receptacles, and locking-plates inserted in the receptacles to retain the spring, the guards and the projections in position therein.

3. In eyeglasses, posts having closed receptacles except as to their ends, which are open, guards having projections passing through the spring and into a wall of the receptacles, and locking-plates inserted in the 95 receptacles to retain the guards, the spring and the projections in position therein.

4. In eyeglasses, a spring and guards forming members which are interlocked by projections formed on one member and passing 100

through and extending beyond said member, posts with receptacles adapted to receive the interlocked members and the extended end of the interlocking projections, and locking-
5 plates introduced into the receptacles in manner to retain all of said members in position therein.

In testimony whereof I affix my signature in presence of two witnesses.

FRANCIS X. GARTLAND.
